US0D1110184S

(12) **United States Design Patent** (10) **Patent No.:** **US D1,110,184 S**
(45) **Date of Patent:** **** Jan. 27, 2026**

(54) **CUFF FOR WATCH**

(71) Applicant: **STEEL AMERICAN LUXURY LLC**,
Winnetka, IL (US)

(72) Inventor: **Nicole Steel**, Winnetka, IL (US)

(73) Assignee: **STEEL AMERICAN LUXURY LLC**,
Winnetka, IL (US)

(**) Term: **15 Years**

(21) Appl. No.: **35/003,086**

(22) Filed: **Jul. 3, 2023**

(80) **Hague Agreement Data**

Int. Filing Date: **Jul. 3, 2023**

Int. Reg. No.: **DM/232860**

Int. Reg. Date: **Jul. 3, 2023**

Int. Reg. Pub. Date: **Nov. 10, 2023**

(51) **LOC (15) Cl.** **11-01**

(52) **U.S. Cl.**

USPC **D11/3**

(57) **CLAIM**

The ornamental design for a cuff for watch as shown and described.

DESCRIPTION

1. Cuff for watch
4. Cuff for watch
- 1.1 : Perspective
- 1.2 : Bottom Perspective
- 1.3 : Front
- 1.4 : Back
- 1.5 : Right
- 1.6 : Left
- 1.7 : Top
- 1.8 : Bottom
- 4.1 : Perspective
- 4.2 : Bottom Perspective
- 4.3 : Front
- 4.4 : Back
- 4.5 : Right
- 4.6 : Left
- 4.7 : Top
- 4.8 : Bottom

The dash-dash broken lines in the drawings represent portions of the cuff for watch and form no part of the claimed design. The other broken lines showing a watch represent environmental subject matter only and form no part of the claimed design. The dash-dot broken lines in the drawings represent a boundary of the claimed design.

1 Claim, 16 Drawing Sheets
